[57] ABSTRACT

A method and means for connecting the electrodes of a gaseous-discharge display panel to the drive circuits which control the potential across the electrodes and thus the production of the gaseous discharge. It is demonstrated that a capacitive coupling, rather than an ohmic coupling, is practical and beneficial from a maintenance standpoint, since the gas display panel may be more easily replaced.

CAPACITIVE-COUPLED CONNECTORS FOR GASEOUS DISCHARGE DISPLAY PANELS

BACKGROUND OF THE INVENTION

1. Field of the Invention

This invention relates to electrical connectors and more particularly to capacitive-coupled connectors for use with gaseous-discharge display devices.

2. Description of the Prior Art

Gaseous-discharge display panels are well known in the prior art. Such devices generally comprise a gas filled envelope which contains a plurality of electrodes arranged in columns and rows thereby producing a matrix. The electrodes are interconnected to associated drive circuits which are used to generate a potential of 15 a magnitude sufficient to cause a discharge in the gaseous space at the intersection of two such electrodes. This discharge is visible, and thus the panel may be used as a display panel. By appropriately selecting which electrodes are connected to the drive circuits, the location of the discharge may be controlled, and a desired pattern may be displayed.

In the prior art, however, the electrical connection between the electrodes forming the matrix and the driver circuits have been made by ohmic contact, for example, by soldering wires or by the use of connector-block terminals. Thus, the gas display panel has been physically integrated with the driver circuits. This integration has been disadvantageous from the viewpoint of reliable maintenance since, when the gas panel must be replaced, the ohmic connection must be destroyed and a new one fabricated. This invention offers the desirable attribute of rapid replacement of a gas panel.

Whenever an isolating capacitance is electrically required or desirable, it is also known in the prior art to fabricate couplers with inherent capacitances, whereby the need for an isolating capacitor as an independent circuit element is obviated. Such a fabrication, for example, is disclosed in U.S. Pat. No. 3,223,884, issued Dec. 14, 1965, an entitled "Gaseous Discharge Device." Such capacitive couplings, with their concomitant ease of mechanical assembly, have not, however, been employed in those coupling situations where an ohmic connection has been thought to be required, for example, in a gaseous-discharge panel. Such ohmic connections are, in turn, subject to the disadvantages mentioned above.

SUMMARY OF THE INVENTION

This invention provides a capacitive coupling for use with gaseous-discharge display panels and thereby eliminates the mechanical disadvantages inherent in the prior art ohmic connection, while still providing sufficient power transfer to operate the panel.

It describes a method and means for the electrical connection of a gaseous-discharge display panel to its associated driver circuits. The display panel is fabricated in such a manner that the electrodes are connected to external land terminals at the periphery of the back side of the panel. The drive circuits are fabricated on a conventional circuit board having its electrical connections made to land terminals on the back side of the circuit board. The land terminals of both the gas display panel and the circuit board are placed in identical positions so that they align with each other when the gas panel is placed adjacent the circuit board. Moreover, the lands are coated with an insulating layer

so that, in effect, a capacitor is formed by the insulating layer between the aligned land terminals.

A capacitive coupling is thus fabricated between the electrodes comprising the gaseous display panel and their associated drive circuits. This capacitive coupling replaces the ohmic connector of the prior art. It offers advantages from a maintenance viewpoint since a gas panel may be rapidly disconnected from its associated drive circuits and, if necessary, a new one connected thereto.

Accordingly, it is an object of this invention to provide between a gaseous discharge display device and its associated drive circuits a coupling which permits rapid replacement of the display panel.

Another object of this invention is to provide between a gaseous discharge display device and its associated drive circuit a coupling which facilitates their electrical interconnection.

A further object of this invention is to provide a capacitive coupling between a gaseous discharge display panel and its associated drive circuits.

BRIEF DESCRIPTION OF THE DRAWING

FIG. 1 is a schematic diagram of a matrix employed 25 in a gas panel used in the invention;

FIG. 2 is a cross-sectional view illustrating the mechanical connection and capacitive coupling between a gas panel and circuit board containing driver circuits for the panel;

FIG. 3 is a schematic diagram of an equivalent circuit of an individual gas cell; and

FIG. 4 illustrates a transmission line model of one complete column of gas cells.

DESCRIPTION OF THE PREFERRED EMBODIMENT

FIG. 1 illustrates a typical matrix of electrodes for a gaseous-discharge display panel of the type which may be employed in the subject invention. A series of first electrodes 10-16 are arranged in columns, and a series of second electrodes 18-24 are arranged in rows. The electrodes are spaced at their intersections. To form a gas panel, the matrix is placed within a gas-filled envelope 25. In operation, a column and a row electrode simultaneously are energized to produce at their intersection a potential of such a magnitude that a discharge occurs through the gas in the space between the electrodes, thereby producing a visible spot of light. If the electrodes are selectively energized, a desired pattern 35 may be generated by the resulting gaseous discharges. A gas panel which may be employed with this invention is more fully described in an article by D.M. Arora et al., entitled "Plasma Display Panel — A New Device for Information Displays and Storage" in the Eighth National Symposium, Society for Information Display, published in May, 1967.

Each electrode of the matrix is connected to a land terminal 26 which is outside the air-tight, gas-filled envelope 25. These land terminals permit the electrodes to be electrically connected to voltage control means, such as associated drive circuits which control the potential between the electrodes and thus the gaseous discharges. In the prior art, as described above, these electrical connections have been made by ohmic connectors. It is a function of this invention to provide a capacitive coupling between each electrode and its associated driver circuit.

According to this invention, the driver circuits are fabricated on a circuit board having its electrical connections made to land terminals which may be aligned with the land terminals of the matrix. The lands are then coated with an insulating layer. Thus, when the gas panel and the circuit board supporting the driver circuits are placed adjacent to each other, a capacitive coupling is achieved by each pair of lands and the intermediate insulating layer. If the gas panel and the circuit board are then mechanically coupled together, there is formed an assembly which provides capacitive coupling and rapid disassembly.

A cross-section of such an assembly is illustrated in FIG. 2. A gas panel 30 has been mechanically coupled to a circuit board 32. The mechanical coupling may be achieved, for example, by a plurality of nuts 34 and bolts 36 which clamp together the panel and board. The circuit board supports the driver circuits 38 which provide the potential to the electrodes within the gas panel assembly 30. Electrical connection between each driver circuit 38 and its associated electrode is achieved by the capacitive coupling formed by lands 40 and 42 and the insulating layer 44. The lands 40 are electrically connected to corresponding electrodes of the gas display panel and correspond to the land terminals 26 in FIG. 1. The lands 42 are attached to the circuit board 32 and are electrically connected to the driver circuits 38.

In operation, the capacitive connector couples the RF energy produced by the drive circuits and also passes the write, read, and the erase pulses which are superimposed upon the RF oscillations generated by the drive circuits. The operation of the capacitive connector and the calculation of the desired magnitude of capacitance will now be discussed.

FIG. 3 represents the equivalent circuit of an individual gas cell, i.e., that area between the electrodes at their intersection. C_i represents the capacitance of the thin insulator separating the electrode from the gas discharge region; C_w represents the capacitance on the inner wall of the thin insulator due to the space charge accumulated from the discharging gas plasma; R_i represents the variable resistance of the gas column; and V_w represents the variable voltage across capacitance C_w due to the residual charges. For typical geometrics, C_w is approximately equal to 3×10^{-3} picofarads and C_i is approximately equal to 80×10^{-3} picofarads. Therefore, the capacitance C_{uf} of an unfired cell is determined by the following equations:

$$1/C_{uf} = 1/C_i + 1/C_w + 1/C_t \quad (1)$$

$$C_{uf} = (C_i C_w) / (2C_w + C_i) \approx 2.80 \times 10^{-3} \text{ pf.} \quad (2)$$

Since the capacitance across the cell, i.e., C_w , is very small for a fired cell, the capacitance of a fired cell C_f is determined by the following equations:

$$1/C_f = 1/C_i + 1/C_t \quad (3)$$

$$C_f = C_i/2 \approx 40 \times 10^{-3} \text{ pf.} \quad (4)$$

FIG. 4 illustrates a transmission line model of one complete column of a matrix of a gas panel. The capacitor C_c represents the coupling capacitor associated with that column electrode and is the value which we are trying to estimate. The capacitor C_1 is the capacitance of the first cell in that column and the capacitor C_{r-1} is the coupling capacitor associated with the first row. Similarly, C_2 , C_3 , and C_n are the capacitances associated with further cells in the column. The capacitors C_{r-2} , C_{r-3} , and C_{r-n} are the coupling capacitors associated with the other rows in the matrix. The equivalent capacitance of one leg in the above transmission line model is determined by the following equation:

$$1/C_{leg} = 1/C_1 + 1/C_{r-1} \quad (5)$$

$$C_{leg} = (C_{r-1} C_1) / (C_{r-1} + C_1) \quad (6)$$

Therefore, the capacitance of the total legs in the transmission line model is determined as follows:

$$C_{total} = (N C_1 C_{r-1}) / (C_1 + C_{r-1}) \quad (7)$$

Substituting the values determined above in equations (2) and (4) for the fired and unfired cells for C_i yields the following results:

$$C_{total \text{ unfired}} = N [(C_{r-1} C_i C_w) / (C_i C_w + C_{r-1} (2C_w + C_i))] \quad (8)$$

$$C_{total \text{ fired}} = N [(C_{r-1} C_i) / (2C_{r-1} + C_i)] \quad (9)$$

To operate the matrix properly with capacitive connectors, the drive circuitry must not dissipate any significant power or experience a high voltage drop across the connection capacitance, that is, the connection capacitance must be much greater than the capacitance of the driven load. Therefore, to determine the size of the coupling capacitance C_c , let us assume a ten percent voltage drop across the coupling capacitance. Hence, C_c must be approximately ten times the total capacitance of the driven load. Therefore, for a column in which all cells are unfired, the following equations determine the value of the coupling capacitance:

$$C_c = 10N (C_{r-1} C_i C_w) / (C_i C_w + C_{r-1} (2C_w + C_i)) \approx (10N-1) (C_i C_w) / (2C_w + C_i) = (10N-1) \times 2.8 \times 10^{-3} \text{ pf} \quad (10)$$

and similarly, the following equations determine the value for a column in which all cells are fired:

$$C_c = 10N (C_{r-1} C_i / 2 C_w + C_i) \approx (10N-1) C_i / 2 = (10N-1) \times 40 \times 10^{-3} \text{ pf} \quad (11)$$

From these equations, it can be seen that a coupling capacitance of, for example, 2.8 picofarads has the capability of driving approximately 10,000 unfired cells or 500 fired cells. These numbers of cells are typical of gas display devices and a capacitor of 2.8 picofarads

can be practically constructed from lead terminals whose dimensions are 0.020 inch times 1 inch. Therefore, such a capacitive connector is feasible under present technology.

While the invention has been particularly shown and described with reference to a preferred embodiment thereof, it will be understood by those skilled in the art that various changes in form and details may be made therein without departing from the spirit and scope of the invention.

What is claimed is:

1. In a gaseous-discharge display device having a gas-filled envelope, a series of first electrodes arranged in columns within said envelope, a series of second electrodes arranged in rows within said envelope and spaced from said first electrodes, and voltage control means coupled to said first and second electrodes for varying the potential between said first and second electrodes, thereby causing a gaseous discharge between said first and second electrodes whereby the gaseous discharge may be produced at selected intersections of said first and second electrodes, the improvement comprising:

a capacitive coupling between said first electrodes and said voltage control means and said second electrodes and said voltage control means for facilitating the connection of said first and second electrodes to said voltage control means and wherein the physical characteristics of the capacitive coupling are such that the capacitance of said capacitive coupling to a first electrode is substantially greater than the input capacitance of said first electrode.

2. The improvement of claim 1 wherein the physical

characteristics of the capacitive coupling are such that the capacitance of said capacitive coupling to a second electrode is substantially greater than the input capacitance of said second electrode.

3. A gas panel assembly comprising:
a flat, gas-filled envelope;
a series of first electrodes arranged in columns within said envelope;
a series of second electrodes arranged in rows within said envelope and spaced from said first electrodes;
a series of flat terminals electrically coupled to said electrodes and arranged around the periphery of said envelope;
a flat, rigid support member;
voltage control means for varying the potential between said electrodes and affixed to said support member;
a series of flat terminals electrically coupled to said voltage control means and arranged around the periphery of said support member; and
means for clamping said support member to said envelope for aligning said terminals on said support member with corresponding terminals on said envelope, whereby said aligned terminals form a capacitive coupling between said electrodes and said voltage control means.

4. The assembly of claim 3 further comprising an insulating layer between the aligned terminals for increasing the capacitance of said capacitive coupling to such an extent that the potential drop across said coupling is a small percentage of the potential drop across said electrodes.
